EDGE TRIMMER FOR ADVANCING SHEET MATERIAL

Samuel S. Miner, Mishawaka, Ind., assignor to United States Rubber Company, New York, N. Y., a corporation of New Jersey

Application February 3, 1954, Serial No. 407,865

10 Claims. (Cl. 164—39.)

This invention relates to a trimmer for sheet material, and more specifically it relates to a trimmer adapted to trim automatically excess coating from a continuously advancing web of coated fabric or the like.

In producing coated fabrics and similar articles, frequently the fabric or other base has applied thereto an excess of coating material which extends beyond the edges of the base. For example coated fabrics are commonly produced by a calender coating process in which a continuous thin coating sheet of rubber, resin or the like several feet wide and of continuous length is produced on a calender. This coating sheet advances continuously through the nip of a final pair of the calender rolls simultaneously with a base sheet of fabric, paper or the like several feet in width and of great length. As the two sheets pass through this nip, the coating sheet is pressed onto the base sheet to form a coated fabric or the like. As this product leaves the nip of these rolls, the coating generally extends beyond the sides of the base some distance, and before the laminate is ready for sale or use this excess should be trimmed therefrom so the base and coating are coextensive in the finished product.

It is an object of this invention to provide a trimmer adapted to trim excess coating material from a base sheet to produce the desired finished product.

In accordance with this invention there is provided a roller that is mounted to roll along the back of the laminate which is to be trimmed. The laminate is led past this roller in such a manner that the roller may contact and roll along the edge of the base sheet. The roller is mounted such that it also may be translated along a fixed path which extends transversely of the base sheet to intercept the line formed by the edge of the base sheet in a substantial angle. Consequently the roller may be positioned such that it will roll either on the base sheet or on the overhanging edge of the coating sheet. In accordance with this invention means are provided to cause the roller to assume a position in its fixed path where it will roll precisely on the edge of the base sheet as the base sheet moves therewith. A knife is mounted in fixed relation to the roller, and is positioned to pierce the laminate. Since means are provided to maintain the roller rolling along the edge of the base sheet, this knife may be mounted to cut the excess coating material from the laminate precisely along the edge of this base fabric as the laminate progresses therewith or the knife may be spaced a predetermined distance from this edge to trim only a part of the coating should such a finished product be desired.

In accordance with this invention the means to maintain the roller rolling precisely along the edge of the base fabric comprises an axle for the roller which is mounted at a slight angle to the line formed by the edge of the base fabric. The roller rotates about this axis and consequently the roller tends to roll at a slight angle to the edge of the base. Consequently as the laminate passes the roller it exerts a force thereon which tends to

2

translate the roller in an angular direction with respect to the edge of the base. Since the roller is mounted such that it may be translated along a fixed path disposed in an angular relation to the edge of the base, the roller may be translated in response to this force. Means are provided to exert a uniform force on the roller tending to resist this translation. This force is selected such that it is great enough to overcome the tendency of the roller to be translated when it is in frictional engagement with one of the elements in the laminate, i. e. the coating or the base, but it is not great enough to overcome this tendency to move when the roller is in frictional engagement with the other element in the laminate. Consequently when the roller is running on the first element of the laminate, the force will move the roller toward the edge of the base until it runs on the other element of the laminate. Conversely when the roller runs on the second element of the laminate, the force on the roller will overcome this fixed force and move the roller toward the first element of the laminate. Consequently a position of equilibrium will be achieved where the roller is running partially on the base and partially on the coating, i. e. along the edge of the base, and the roller will follow this edge should it deviate from a straight line as the laminate is led past the roller.

In one specific embodiment of this invention the roller comprises a wheel that is mounted on an axle. This axle is mounted on a carriage in a manner such that the wheel is canted inwardly slightly with respect to the edge of the base. The fixed force is provided by a second wheel mounted on an axle on the same carriage. This second wheel is canted outwardly toward the edge of the base; consequently the two wheels are canted inwardly toward each other and the second wheel runs always on the base. The carriage is mounted for movement along a shaft disposed in an angular direction to the edge of the base. A knife is mounted on the carriage in fixed relation in space to the first wheel.

As the laminate is led past this carriage in contact with both wheels, the second wheel which is always in contact with the base will, because of its canted position in relation to the direction of movement of the laminate therewith, tend to move the carriage along the shaft in one direction; i. e. the second will tend to run off the base. Conversely the first wheel which is adapted to run along the edge of the base will tend to move the carriage in the other direction along the shaft; i. e. the first wheel will tend to run onto the base. The surfaces of the wheels are made such that when both wheels are running on the base, the second wheel has a greater frictional drag thereon than the first and consequently the carriage will move in response to the urging of this second wheel. However the surfaces of the wheels are such that when the first wheel is running on the coating, it exerts a force on the carriage sufficient to overcome that of the second wheel running on the base. This may be achieved easily because the natures of the coating and base are such that the coating will exert a greater drag on the wheel than will the base. Consequently as the fabric is led past the carriage, the carriage will assume a position on its shaft such that the first wheel is running partially on the overhanging edge of the coating and partially on the base and this wheel will follow this edge of the base as the laminate is led therewith. A knife is mounted on the carriage in a position to trim the laminate, and since the carriage follows the edge of the base this knife will trim the excess coating from the laminate.

For a better understanding of the nature of this invention, reference should be had to the following detailed description when read in conjunction with the accompanying drawing, wherein:

Fig. 1 is an end elevational view of the trimmer in accordance with this invention showing it mounted in the exit end of the nip of a pair of calender rolls and illustrating the use of the trimmer to trim excess coating stock from the edge of a coated fabric; and

Fig. 2 is a plan view of the trimmer in accordance with this invention looking substantially along line 2—2 of Fig. 1.

Referring now to the drawing, there is illustrated an embodiment of the trimmer in accordance with this invention which is well suited for trimming excess coating stock from a sheet of coated fabric. In the drawing, this trimmer is illustrated as running in the exit end of a nip of calender rolls 10, 11. These rolls may constitute the final pair of rolls of a calender used to produce a coated fabric. As is well known in the rubber industry, the calender (not shown) calenders a continuous sheet of coating such as rubber, resin or the like to the desired gauge, and a base sheet such as fabric, paper or the like is then led simultaneously with this coating through a final pair of calender rolls where the coating is pressed onto the base sheet to produce the coated fabric. Since the calender and the method of calender coating fabrics are well known and form no part of this invention, they will not be further described here.

As best shown in Fig. 2, the laminate CF as it leaves the calender has the coating C applied to the base sheet F. Generally there is a narrow excess of coating 12 which overhangs the edge 13 of the base sheet F. It is desirable that this excess coating 12 be trimmed from the base sheet along the edge 13 of the base sheet, so that the coating and base sheet are coextensive in the finished laminate. The trimmer in accordance with this invention is well adapted to trim this excess 12 from the coated sheet continuously and automatically.

In the embodiment shown in the drawing, the trimmer comprises a first wheel 14 which is rotatably mounted by means of bearings 15 on an axle 16. This axle 16 is mounted at a slight angle to the edge 13 so that the wheel 14 is canted inwardly slightly toward the base sheet from this edge. This wheel 14 is urged against the laminate CF and against the roller 10 of the calender by means to be described, so that as the laminate CF advances in the direction indicated by the arrow it will tend to rotate the wheel or roller 14. As seen in Fig. 2, the movement of the laminate CF past the roller 14 will exert a force on this roller which tends to make it roll off the excess coating 12 and onto the sheet F, i. e. downwardly as seen in Fig. 2. This axle 16 is mounted on a carriage that is constrained to move only along a path which lies in an angular direction with respect to the edge 13 of the base sheet.

In the embodiment shown in the drawing, this carriage comprises a post 17 that is fixed in a mounting 18 therefore. The post 17 carries on its opposite end a second wheel 19 that is adapted to run on the base sheet F. As shown in Fig. 2, this wheel 19 is rotatably mounted by means of bearings 20 on an axle that is canted toward the edge 13 of the base sheet F so that the wheels 14, 19 are canted inwardly toward each other. Consequently as the wheel 19 rolls along the base F it will tend to roll off the base onto the excess coating 12, i. e. upwardly as seen in Fig. 2. Therefore it will be seen that rollers 14 and 19 each exert a force on the post 17, which forces since they act in opposite directions tend to counterbalance each other.

The mounting 18 for the post 17 is fixed to a sleeve 22 by connecting member 21. This sleeve 22 embraces a shaft 23 that extends in an angular direction with respect to the edge 13 of the base sheet. In the embodiment shown, the shaft 23 extends substantially at right angles to the edge 13 entirely across the calender. The sleeve 22 is mounted on the shaft 23 for sliding movement longitudinally of this shaft by means of three spaced rollers 24 at each end that are mounted on axles 25

carried by straps 26 which are fixed to the sleeve 22. Consequently the sleeve 22 may move freely along the shaft 23 in response to the urgings of the rollers 14, 19 to move these wheels and a cutting knife, to be described, laterally of the laminate CF. Because the sleeve 22 floats on shaft 23, the sleeve may also be rotated about this shaft, and consequently the rollers 14, 19 may be moved into or out of engagement with the laminate CF.

A lever 27 fixed to the sleeve 22 on the opposite side thereof from post 17 carries a counterweight 28 thereon. This counterweight tends to rotate the sleeve 22 about the shaft 23, and consequently urges the rollers 14, 19 upwardly into firm engagement with the laminate CF and the upper calender roll 10. This sleeve 22 also carries a knife mounting 29 to which a knife 30 is fixed by means of bolt 31. The blade of knife 30 is positioned to pierce the laminate CF substantially in line with wheel 14 in the embodiment shown.

In the operation of the trimmer, the wheels 14 and 19 are urged against the laminate CF by the counterweight 28. As this laminate runs past these wheels, they will rotate about their axes, and because of their canted position, they will also tend to slide along the laminate. Consequently the wheel 14 will urge the carriage downwardly as seen in Fig. 2 and wheel 19 will urge the carriage upwardly as seen in the same figure. Since the wheel 19 is positioned to run always on the base sheet F it will exert a uniform force on the carriage tending to move it along the shaft 23. As the wheel 19 moves the carriage towards the edge 13 of the fabric, the wheel 14 will be moved outwardly toward the overhanging coating 12. The device is constructed in a manner such that the force exerted by the wheel 14 on the carriage when the wheel 14 is running on the base F is less than the force exerted by the wheel 19 on the carriage when wheel 19 is also running on the base F. Consequently the carriage will move to the edge 13 of the base F until the wheel 14 is running on the overhanging coating 12. At that point since the coating C offers a much greater frictional resistance to the sliding of the wheel 14 there along than does the base F of fabric, paper or the like, the force exerted on the carriage by the wheel 14 will increase materially. Wheel 14 is constructed such that the force exerted by it when it is on the coating is greater than the force exerted on the carriage by the wheel 19 running on the base F. Consequently the wheel 14 will then tend to move the carriage to a position where the wheel 14 is running on the base F.

A position of equilibrium will be achieved when the wheel 14 is running precisely along the edge 13 of the base F, so that the wheel 14 is running partially on the base F and partially on the overhanging portion 12 of the coating C. Consequently if the edge 13 on which the wheel 14 is running remains straight, the carriage will assume a fixed position on shaft 23. However, should the edge 13 depart from a straight line, the wheel 14 would be running on either the base or the overhanging coating 12 depending upon the direction of departure, and the unbalance thus set up would shift the carriage along shaft 23 until the wheel 14 were once again running along the edge 13 of the base. Thus it will be seen that the wheel 14, and consequently the carriage, will follow precisely the edge of the base as it is led therepast. The knife 30 being mounted on this carriage will similarly follow the edge 13 of the base to trim the overhanging portion 12 of the coating C from the laminate CF. This edge 12 as best shown in Fig. 1 may be led with the roll 10 upwardly into the bank of coating stock to be reused therein if desired.

The forces exerted on the carriage by the wheels 14 and 19 may be balanced by any suitable construction of the apparatus. In the embodiment illustrated this is done conveniently by knurling the surface of wheel 19, and by cutting a plurality of circumferential grooves 38 in wheel 14. When the grooved and knurled wheel are

both running on base F, the knurled wheel will exert a greater thrust on the carriage than the grooved wheel, but when grooved wheel 14 is running on the excess coating 12, the grooved wheel will exert a greater thrust on the carriage than the knurled wheel running on the base F. Alternatively, the surfaces of wheels 14 and 19 may be made more or less similar, and the angles of cant of these wheels may be adjusted in a manner about to be described until the desired balance is reached.

The trimmer in accordance with this invention may be made adjustable to adapt it to trim excess coating having different properties from base sheets or to provide the desired thrust balance between the wheels. Thus in the embodiment shown in the drawing, the axle 16 of wheel 14 is adjustably mounted on post 17 so that the degree of canting of the wheel 14 with respect to the edge 13 may be varied as desired. This axle 16 is mounted on a carrier 32 which is mounted on a pivot 33 at the end of post 17. The carrier 32 is fitted in a slot in post 17 and on its inner end has an inclined shoulder 34 that is projectible above the surface of the post 17. The post 17 has a threaded portion adjacent this inclined shoulder 34, and a nut 35 is threaded thereupon for movement longitudinally of the post 17. As the nut 35 is moved toward wheel 14 along the threads on post 17, a bearing surface on nut 35 bears against shoulder 34 to depress this shoulder within the slot in post 17 and thus pivot carrier 32 about its pivot 33 to thereby increase the angle between shaft 16 and edge 13. A spring 36 held by set screw 37 extends through an opening in post 17 to bear against the under edge of carrier 32 to urge shoulder 34 against the nut 35. Consequently if the nut 35 is backed off shoulder 34, spring 36 will urge carrier 32 to pivot about its pivot 33 and thereby decrease the angle of shaft 16 with respect to the edge 13 of the base F. In this manner the inclination of wheel 14 with respect to the direction of travel of the laminate CF therewith may be varied to vary the lateral thrust exerted by this wheel on the carriage. By thus varying the inclination of wheel 14, the apparatus may be adapted to work with gum stocks or bases having different frictional characteristics with respect to the surface of the wheel 14. So also if desired the angle of inclination of wheel 19 with respect to edge 13 may be varied by similarly mounting wheel 19.

So also the position of knife 30 with respect to wheel 14 may be varied. In the embodiment shown in the drawing this is accomplished by providing a hollow mounting 18 through which the post 17 slidably extends. The post 17 may be adjusted to any desired position within mounting 18, and the post 17 may be tightened in such position by means of a set screw 39 which extends through the mounting 18 and is adapted to bear against the post 17 therein. Also the apparatus is adaptable to trimming the edge 12 from either side of the coated laminate CF. This may be provided by fixing the mounting 18 pivotally in the member 21, so that mounting 18, post 17 and wheels 14 and 19 may be rotated about an axis through member 21 and extending at right angles to the axis of post 17.

Having thus described my invention, what I claim and desire to protect by Letters Patent is:

1. A trimmer adapted to trim sheet material when advancing in a given direction and having a juncture of two materials having different co-efficients of friction with a given object, said juncture having a component of its length extending in the direction of advance of said sheet material, said trimmer comprising a carriage, means adapted to support said carriage for movement along a path disposed in angular relation to the juncture and having a component of its length transverse to the direction of advance of the sheet material, a roller on said carriage adapted to be positioned to roll along the juncture in frictional engagement with the sheet material, said roller being canted on said carriage with respect to the direction that the sheet material is adapted to advance 65

past the carriage and in a direction to roll toward the material having the lesser co-efficient of friction with said roller, means to urge said carriage in a direction adapted to position said roller on that material having the greater co-efficient of friction with said roller, said means being adapted to develop a force which is sufficient to counteract the transverse force of said roller on said carriage when said roller is rolling along the juncture of the two materials, and cutting means carried by said carriage adapted to cut the sheet material, whereby said carriage is adapted to be moved along the path to a position wherein said cutting means may be positioned in substantially constant relation with the juncture of the sheet material.

15 2. A trimmer adapted to trim a web of laminated sheet material when advancing in a given direction and having a juncture formed by an overhanging edge of one material having a different co-efficient of friction with a given object than the other material in the laminate forming the juncture, said juncture having a major component of its length extending in the direction of advance of said sheet material, said trimmer comprising a carriage, means adapted to support said carriage for movement along a path disposed in angular relation to the juncture and having a component of its length transverse to the direction of advance of the sheet material, a wheel on said carriage adapted to be positioned to roll along the juncture in frictional engagement with the sheet material, said wheel being canted on said carriage with respect to the direction that the sheet material is adapted to advance past the carriage and in a direction to roll toward the material having the lesser co-efficient of friction with said wheel, means to urge said carriage in a direction adapted to position said wheel on that material having the greater co-efficient of friction with said wheel, said means being adapted to develop a force which is sufficient to counteract the transverse force of said wheel on said carriage when said wheel is rolling along the juncture of the two materials, and a knife carried by said carriage adapted to cut the sheet material as it advances, whereby said carriage is adapted to be moved along the path to a position wherein said knife may be positioned in substantially constant relation with the juncture of the sheet material.

45 3. A trimmer adapted to trim a web of laminated sheet material when advancing in a given direction and having a juncture formed by an overhanging edge of one of the materials in the laminate that has a different co-efficient of friction with a given object than the other material in the laminate forming the juncture, said juncture having a major component of its length extending in the direction of advance of said sheet material, said trimmer comprising a carriage, means adapted to support said carriage for movement along a path disposed in angular relation to the juncture and having a component of its length transverse to the direction of advance of the sheet material, a first wheel on said carriage adapted to be positioned to roll along the juncture in frictional engagement with the sheet material, said wheel being canted on said carriage with respect to the direction that the sheet material is adapted to advance past the carriage and in a direction to roll toward the material having the lesser co-efficient of friction with said wheel, a second wheel on said carriage adapted to be positioned to roll always on the material having the lesser coefficient of friction with said first wheel and in frictional engagement therewith, said second wheel being canted on said carriage with respect to the direction that the sheet material is adapted to advance past the carriage and in a direction to roll toward the material having the greater coefficient of friction with said first wheel, and cutting means carried by said carriage adapted to cut the sheet material, whereby said carriage is adapted to be moved along the path to a position wherein said cutting means may be positioned

in substantially constant relation with the juncture of the sheet material.

4. A trimmer adapted to trim a coated sheet when advancing in a given direction and having a juncture formed by an overhanging excess of coating having a different coefficient of friction with a given object than the base sheet, said juncture having a major component of its length extending in the direction of advance of said coated sheet, said trimmer comprising a carriage, means adapted to support said carriage for movement along a path disposed in angular relation to the juncture and having a component of its length transverse to the direction of advance of the sheet material, a first wheel on said carriage adapted to be positioned to roll along the juncture in frictional engagement with the coated sheet, said wheel being canted on said carriage with respect to the direction that the coated sheet is adapted to advance past the carriage and in a direction to roll away from the overhanging excess of coating and toward the sheet, a second wheel on said carriage adapted to be positioned to roll always on the sheet and in frictional engagement therewith, said second wheel being canted on said carriage with respect to the direction that the coated sheet is adapted to advance past the carriage and in a direction to roll off of the sheet and onto the overhanging excess of coating, and a knife carried by said carriage adapted to cut the excess of coating, whereby said carriage is adapted to move along the path to a position wherein said knife may be positioned in substantially constant relation with the juncture formed by the overhanging excess of coating.

5. A trimmer adapted to trim a web of coated sheet material when advancing in a given direction and having a juncture formed by an overhanging excess of coating having a greater coefficient of friction with a given object than the base sheet, said juncture having a major component of its length extending in the direction of advance of said coated sheet material, said trimmer comprising a carriage, means adapted to support said carriage for movement along a path disposed in angular relation to the juncture and having a component of its length transverse to the direction of advance of the sheet material, an axle carried by said carriage, said axle being canted inwardly with respect to the direction that the coated sheet is adapted to advance past the carriage, a first wheel rotatable on said axle and adapted to be positioned to roll along the juncture in frictional engagement with the coated sheet material, a second wheel carried by said carriage

adapted to be positioned to roll always on the base sheet and in frictional engagement therewith, said second wheel being canted on said carriage with respect to the direction that the sheet material is adapted to advance past the carriage and in a direction to roll toward the overhanging excess of coating, and a knife on said carriage adapted to cut the overhanging excess, whereby said carriage is adapted to be moved along the path to a position wherein said knife may be positioned in substantially constant relation with the juncture formed by the overhanging excess of coating.

5 6. A trimmer in accordance with claim 5 wherein said axle is movable to vary the angular relation between said first wheel and the line presented by the advancing edge 15 of said sheet.

7. A trimmer in accordance with claim 5 wherein said first wheel has a lesser coefficient of friction with said sheet than said second wheel.

8. A trimmer for an advancing web of coated sheet 20 material having an overhanging excess of coating having a greater coefficient of friction with a given object than the base sheet, the juncture between said excess of coating and said sheet material having a component of its length extending in the direction of advance of said coated sheet material, comprising a shaft extending transversely of the advancing web, a carriage on said shaft mounted for movement there along, a first wheel on said carriage positionable to roll along the edge of said sheet, said wheel being canted with respect to the edge of said sheet 25 30 in a direction to roll toward the sheet, a second wheel on said carriage adaptable to roll always on said sheet, said second wheel being canted inwardly toward said first wheel, said second wheel having a surface of greater coefficient of friction with said sheet than said first wheel, 35 said wheels being adapted to position said carriage along said shaft in substantially constant relation to said edge and a knife carried by said carriage positioned to cut said web along the line which said first wheel traverses.

9. A trimmer in accordance with claim 8 wherein said 40 carriage is mounted for rotatable movement about said shaft, and including a counterweight on said carriage urging said wheels in contact with said web.

10. A trimmer in accordance with claim 8 wherein said first wheel is mounted on an axle and including movable 45 means supporting said axle to vary the degree of cant between said first wheel and the edge of said sheet.
